UNITED STATES PATENT OFFICE.

PAUL F. RAMM, OF OAKLAND, CALIFORNIA.

CONCRETE-FORM STAY.

Application filed June 25, 1925. Serial No. 39,451.

My invention is a concrete-form stay of the type adapted to be readily assembled and to extend between the outside studdings of a form, thereby holding the sheeting forming the mold for the concrete. The stay is left imbedded in the concrete.

My present stay is an improvement over that of my Patent #1,259,442 March 12, 1918, for concrete-form stay and over that 10 of my Patent #1,550,000 Aug. 18, 1925, for concrete-form stays. In this application the form stay is made in two parts; and an object of my invention is to devise a connecting means whereby either of the 15 tie members may be secured to the other by hooking therein from their inner ends or by threading through the outer ends which engage and are driven into the studs.

My tie is made in the usual shape with 20 straight shanks and right angle bends at the outer ends forming prongs to be driven into the studding, while the inner end of one of the elements is formed with a single loop, having the end of the wire crossing and pressing against the shank. The other tie 25 element has a right angular bend parallel to its prong and then a longitudinal bend parallel to its shank, forming a locking end. Thus this locking end is off-set from the shank and engages the loop in the other tie 30 member substantially in a direct line parallel to the shank of the looped tie member.

My invention will be more readily understood from the following description and 35 drawings in which:—

Figure 1 is a perspective view of a concrete-form with my concrete-form ties in 40 place and ready to connect, showing the manner of embedding the ties in the concrete, securing the prong end to the studding and the studding holding the concrete in place.

Figure 2 is a small detail showing the opposite way of threading the tie members 45 to that shown in Figure 1.

Figure 3 is a plan view of my concrete-form tie with the two tie elements connected and locked.

Figure 4 is a detail of the tie elements 50 disconnected to show the form of loop on one member and the form of locking hook on the other member.

Figure 5 is an elevation of Figure 3 in 55 the direction of the arrow 5, showing the manner in which the hook of one member en-

gages and locks the loop of the other member.

Referring to the drawings the concrete-form is indicated generally by the numeral 1 and is built up of studs 2, spaced along opposite sides of the form, and wood sheathing 3, held in place by the studs. The studs are held in place by my form ties 4 the prongs of which are embedded in the studs by being hammered therein. The concrete 5 is then filled in the mold or form and tamped if desired, the form ties being left embedded in the concrete if desired, as indicated at 6 in Fig. 1. The usual practice is to leave the form-ties embedded in the concrete and to remove the studs and sheathing.

My form tie is constructed of heavy wire and in two parts. Each part has a shank 6 and 7 with prongs 8 and 9 bent at right angles to the shank and the prongs are preferably bevelled at 10 and 11 to cause them to incline slightly inwardly when driven into the studs. The member 7 is shown with a loop 12 formed by bending the wire 80 into a circle with the end 13 projecting slightly above or level with the top of the shank 7. The end 13 of the loop is brought up on the side of the shank 7 preferably on the same side as in the prong 9.

The other element of the tie, having the shank 6, is shown with a right angular bend 14 forming an offset for the locking stem 15, which is formed by another right angular bend 14', the stem 15 being preferably 90 parallel to the shank 6 in direction. As shown in Figure 3 the bends 14 and 14' are spaced sufficiently to form a short shank 16 so that when the two members are hooked together they will form a species of lock. It is preferable to form the right angular bend 14 of such a radius that its inner curve 17 will engage the edge 18 of the loop or eye 12. The inner edge 19 of the stem 15 engages the outer edge 20 of the end 13 of the loop and presses it against the shank 7.

My form-stay may either be assembled by threading the prongs 8 through the loop 12 or by inserting the stem 15 through the loop or eye in the reversed direction. This 105 is the manner shown in Figure 1 in which the element with the loop is shown driven into one of the studs. In Figure 2 another method of connecting the elements of the tie is shown by first securing the hook to a 110

stud, by driving the prong 8 therein, and passing the eye over the off-set stem 15 and giving it a twist into engagement with the short shank 16.

5. My invention could be changed considerably in detail without departing from the spirit thereof, for instance, the loops could be formed on the opposite side from that shown and the hook member reversed to engage and lock such reversed loop.

10. Having described my invention, what I claim is:—

1. A form tie comprising in combination a plurality of wire members, one member 15 having an eye formed by bending the wire into a loop and the other member having its inner end offset from the main wire, threaded through the eye with the end bearing against the free end of the loop.

20. 2. A form tie comprising in combination a plurality of wire members, one member having an eye formed by bending the shank of the wire in the loop, the other member having two right angular bends at the end 25 of its shank with a stem extending parallel to its stem and positioned, when threaded through the eye, parallel to the stem of the first mentioned member.

3. A form tie comprising in combination 30 a plurality of wire members having shanks, the shank of one member being bent into a loop, with the end of the loop engaging

the shank at the side thereof, the other member having a shank formed with two right angular bends and with a short stem 35 offset and projecting beyond its shank element, said stem, when threaded through the loop and positioned in the work, being parallel to the shank of the first mentioned member and engaging the free end of the loop 40 formed on the said first mentioned member.

4. A form tie comprising in combination a plurality of wire members connected together at their inner ends, one of said members having a shank 7 and a prong 9 at right angles thereto at its outer end and a loop 12 at its inner end, having the end 13 of the loop on the same side of the shank as the prong 9 and engaging the side of the shank, the other member of the tie having a shank 6 50 with a prong 8 bent at right angles thereto at its outer end and having two right angular bends 14 and 14' forming a short shank 16 substantially parallel to the prong 8 and extending in the same direction and an off-set stem 15 parallel to and extending in the same direction as the shank 6, said wire members having, when connected, the short shank 16 extending through the loop 55 12 and the off-set stem 15 engaging the end 13 of the said loop, said stem being substantially parallel with the shank 7.

In testimony whereof I affix my signature.

PAUL F. RAMM.
